9 Claims. (Cl. 272—85)

The present invention relates to a metal hoop that can be used in sports for many different purposes, that is to say it may be used for swinging and throwing (in the manner of a discus), or for trundling and more particularly for jumping over and through, and for crawling through while it is rolling.

If a metal hoop is to be used for throwing it fulfills this purpose far better if it be made sufficiently heavy and is provided with a suitable grip, and if furthermore it be so constructed that it is not damaged or deformed by impact with the ground.

If the hoop is to be used for jumping through or jumping over, it is advisable to provide means to render these exercises increasingly difficult. Finally, in both cases it may be advantageous to construct the hoop so that it can be taken to pieces so as to be easily carried.

All these purposes are served by the hoop according to the invention; this is effected principally by the use of one or more members that can be secured in any desired position around the periphery of the hoop, each body consisting of two parts connected together, which grip a section of the hoop in the manner of tongs and are at the same time of such shape that the outer tread of the hoop is left uncovered. This member may be so constructed that it can be used as a grip for throwing the hoop, and furthermore it may act as a lock for the loop at the positions where the hoop is divided, and also it may be used as securing means for spoke-like members that are applied for stiffening the hoop when it is used as a discus, and when used in jumping exercises may serve as means for varying the free open space within the hoop.

The accompanying drawings illustrate by way of example a number of different hoops for use in sports constructed according to the invention.

Figure 1 shows a hoop *a* in its simplest form for throwing; it is provided with a member *b* secured to the periphery of the hoop, this member forming a convenient grip for the hand of the thrower. A second grip may be provided diametrically opposite the grip *b* as shown in dotted lines, or a number of the grips may be distributed around the periphery of the hoop to make it heavier. The hoop is advantageously made of an elastic material of great tensile strength such as spring steel or beryllium bronze, and it may be solid or hollow, and it may moreover be circular in cross-section, or better still elliptical or be of any other shape in cross-section, that is, wider one way of the plane than in

the other. It is particularly insensitive to shocks if it be made of a number of braided or twisted wires *a'*, (as shown in Figures 1a and 1b) the wires being held together by strips of material wound round or provided with a rubber covering *a''* which may be vulcanized when in position.

Figure 2 illustrates by way of example a section of a hoop provided with two clamping members *b* one of which has a hole *b°* for the securing of stiffening members *c*. A modified form of the gripping member is shown at *b'*, shown in cross-section in Figure 3. The stiffening members that serve to prevent deformation, consist advantageously of wires or bicycle spokes provided at each end with a rivet head. As will be seen from Figure 3 the clamping body *b* (or *b'*) consists of two parts held together by screws *d* and clamped to the hoop *a*. The parts are so shaped that the greater part of them lie within the hoop but do not completely surround the metal of the hoop. As shown in Figure 4 the wires *c* are disposed radially in the hoop, one end of the wires engaging in a small centrally disposed ring *e*; according to Figure 5 the wires *c* are disposed to form a triangle and are provided with tensioning members *c'* which on rotation regulate the length of the wires in known manner. The clamping members *b* shown in Figure 1 may at the same time serve as members for joining together the sections of the hoop when this is built up of two or more parts.

Figure 6 shows a half of such a locking member, and

Figure 7 shows the complete locking member in cross-section. Each lock consists of two clamping jaws *b*₁ and *b*₂ which are held together by screws *d* and which are formed on one side like tong grippers, while on the other side they bear directly against each other at *f* by projecting parts. In order that the two ends of the hoop *a* may be held in position they are provided with beak-like projections *a°* or similar projections which fit into suitable recesses in the jaws *b*₁ or *b*₂ or lie against stops such for example as screws *d*. A modified construction of the locking member is shown in cross-section in Figure 8 for use with a hoop that is built up of braided wires, and is provided at the ends with extensions by flattening out the metal of the hoop or by pouring-in additional metal. Alternatively the two jaws of the clamping body may be provided with projections and the ends of the hoop sections with recesses, or the screws *d* may engage in suitable grooves provided at the ends of the

hoop. The two jaws may be connected together by hinges at *f*.

Figures 9 and 10 show a clamping body *b* which is of such construction that it is adapted to serve 5 as a locking member for the hoop and as securing means for adjustable spoke-like members, which when moved, change the free open space within the hoop when it is used for jumping through or crawling through. The jaw *b* is provided with an extension *b* having a hole in it into which fits a rotating pin *g* advantageously slotted and resilient so that it is tightly held in 10 position by friction. The pin *g* is provided with a sleeve *g*', the hole being at right angles to the axis of the pin into which engages the resilient 15 pin *g* of similar construction whose end *h*' is employed for securing the spoke *i*.

Thus the spokes may be twisted from the position shown diagrammatically in Figure 11, in 20 which the largest opening in the hoop is adjusted into any other position as shown for example in Figure 12 in which the free open space within the hoop is reduced as shown by the dotted circle, so as to make it more difficult to jump or 25 crawl through. At the same time the spokes *i* may be moved out of the position shown in cross-section in Figure 13 to both sides according to Figure 14 in order to increase the difficulty of jumping over the rolling hoop. The spokes may 30 advantageously be provided at their free ends with balls *i*' to avoid danger.

If the hoop is to be used only for jumping exercises the hinged-on members *b* may be soldered on and in that case may be of more simple construction as shown in Figures 15 and 16.

Figures 17 and 18 illustrate a modified construction of the adjustable members for altering the free open space within the hoop. Each two adjacent clamping members *b* are connected together by flexible members *k* and for the purpose members such as wires in the form of helices may be employed.

By altering the distance between the two members *b*, the members *k* can be changed from the 45 stretched position as shown in Figure 17 into a curved position as shown in Figure 18 so that the free open space within the hoop is reduced. The clamping members *b* may both be adjustable or one of each may be secured to the hoop and 50 soldered on as shown in Figures 15 and 16. It will be understood that some of the members *b* may serve as locking members in the case of a hoop built up from a number of sections.

In jumping and more particularly to facilitate 55 crawling through the rolling hoop it is advantageous to form the hoop so that its rolling movement may be retarded periodically. For the purpose irregularly shaped hoops such as elliptical 60 hoops may be employed. The same purpose is attained more simply by means of clamping members according to the invention, that is to say by securing one or more such members on one side of the hoop or asymmetrically so that 65 the weight of the hoop is unevenly distributed.

What we claim as new and desire to secure by Letters Patent of the United States, is:

1. A metal hoop for athletic exercises with at 70 least one jointing point on the periphery and provided with a plurality of clamping members, each member consisting of two jaws connected together and lying on the inside of the hoop, at least one of the said members forming a hand grip and at least one of them serving as a locking 75 means for joining the ends of the hoop, said ends

increasing in cross-section towards the joint and being fitted into interlocking recesses of the jaws.

2. A metal hoop for athletic exercises with at least one jointing point on the periphery and provided with a plurality of clamping members, each member consisting of two jaws connected together and lying on the inside of the hoop, a number of these members being supports for blocking members and at least one of the said clamping members serving as a locking means for joining the ends of the hoop, said ends increasing in cross-section towards the joint and being fitted into interlocking recesses of the jaws.

3. A metal hoop for athletic exercises with at least one jointing point on the periphery and provided with a plurality of clamping members, each member consisting of two jaws connected together and lying on the inside of the hoop, the members being distributed in equal distances and connected together in pairs inside the hoop by 20 tensioning members and at least one of the said clamping members serving as a locking means for joining the ends of the hoop, said ends increasing in cross-section towards the joint and being fitted into interlocking recesses of the jaws.

4. A metal hoop for athletic exercises with at least one jointing point on the periphery, being composed of braided wire of a strong and elastic material and provided with at least one clamping member consisting of two jaws connected together and lying on the inside of the hoop, the said clamping member being formed both as a hand grip and as a locking means for joining the ends of the braided wire, said ends being bent relative to the periphery of the hoop and held in 35 position by recesses of the said jaws.

5. A metal hoop for athletic exercises provided with at least one jointing point on the periphery, the two ends of the hoop being connected at each jointing position by a locking member, 40 said locking member consisting of two jaws touching one another only by projecting borders at the edges furthest from the periphery of the hoop and pressed together by screw connection in the middle part, the jaws lying on the inside of 45 the hoop and leaving the tread uncovered, said ends of the hoop increasing in cross-section towards the joint and being fitted into interlocking recesses of the jaws.

6. A metal hoop for athletic exercises provided 50 with at least one jointing position on the periphery, the two ends of the hoop being connected at each jointing point by a locking member, said locking member consisting of two jaws which lie on the inside of the hoop and leave its tread uncovered and of two screws for pressing the two bodies together, the screws forming stops for beak-like projections at the ends of the hoop and thus preventing the latter from springing out.

7. A metal hoop for athletic exercises provided 60 with a plurality of blocking members distributed around the periphery and being of such a radial dimension as to leave a free opening in the center of the hoop, a hinge with an axle perpendicular to the plane of the hoop connecting each blocking member and the inside of the hoop, this hinge connection permitting to alter the position of each blocking member as to the distance from the center point of the hoop, and clamping means on the hinge for holding each blocking member 70 in the adjusted position by friction.

8. A metal hoop for athletic exercises provided 75 with a plurality of blocking members distributed around the periphery and being of such a radial dimension as to leave a free opening in the cen-

ter of the hoop, each blocking member being fastened to the hoop by at least one jaw member lying on the inside of the hoop and leaving its tread uncovered, a hinge with an axle perpendicular to the plane of the hoop being inserted between each blocking member and each jaw member, this hinge connection permitting to alter the position of each blocking member as to the distance from the center point of the hoop, and 5 clamping means on the hinge for holding each blocking member in the adjusted position by friction.

10 9. A metal hoop for athletic exercises provided with a plurality of blocking members distributed

around the periphery and being of such a radial length as to leave a free opening in the center of the hoop, a double hinge with axles within and perpendicular to the plane of the hoop connecting each blocking member and the inside of the hoop, 5 this double hinge connection permitting to alter the position of each blocking member as to the plane and to the distance from the center point of the hoop, and clamping means on each hinge for holding each blocking member in the adjusted 10 position by friction.
